UNITED STATES PATENT OFFICE.

INGEBRIGT J. GLERUM, OF DEVILS LAKE, NORTH DAKOTA.

ROAD DRAG.

Application filed October 31, 1921. Serial No. 511,734.

To all whom it may concern:

Be it known that I, INGEBRIGT J. GLERUM, a citizen of the United States, residing at Devils Lake, in the county of Ramsey and State of North Dakota, have invented certain new and useful Improvements in Road Drags; and I do declare the following to be a full, clear, and exact description of the invention, such as will enable others skilled in the art to which it appertains to make and use the same.

This invention relates to an improved road drag, and it has for its principal object to generally improve upon devices of this class by providing one of extreme simplicity and durability which will effectively level the road surface as accurately as possible, will remove high spots, will pulverize large lumps of dirt, and will drag the loose dirt into and fill hollows.

Another and very important object of the invention is to provide a road drag which is composed of a plurality of relatively movable sections, preferably in the form of substantially square diamond shaped open frames which directly contact the ground, novel connectors being employed for attaching the various frames to one another and the connections being such that the forward portion of the drag is flexible, whereas the rear or remaining portion is substantially rigid, that is, the rear cross rows of frames are held in the same horizontal plane to prevent dirt which has been deposited in small hollows from being dragged out by this portion of the device.

A further object of the invention is to provide a drag of this class in which the substantially square or diamond-shaped frames are arranged in transverse and longitudinal rows with at least one corner of each frame disposed toward the front so that the adjacent side portions thereof will deflect the loose dirt toward the sides of the road and in front of adjacent frames to be evenly spread.

A further object of the invention is to provide a road drag wherein all the parts thereof are readily disconnectible to enable the entire device to be rendered very flexible for use on common country roads which do not have to be leveled with extreme care and accuracy.

A still further object of the invention is to devise a device of this class wherein the number of frames employed in forming each

row are equal, thus permitting the hitching means to be connected with any side of the frames for pulling the drag transversely across the road or in a reverse direction. 60 This is advantageous also in that it enables the sides of the frames to be worn evenly.

Other objects and advantages of the invention will be apparent during the course of the following description. 65

In the accompanying drawings forming a part of this specification and in which like numerals are employed to designate like parts throughout the same:

Figure 1 is a top plan view of a road drag 70 constructed in accordance with this invention showing the preferred embodiment.

Figure 2 is a side elevational view thereof.

Figure 3 is a top plan view of a slightly modified form of the invention. 75

Figure 4 is an enlarged detail sectional view showing the novel connectors for the frames.

Figure 5 is another slightly modified form of the invention showing substantially 80 rhombic frames employed.

Referring to the construction of the drag specifically, it will be seen that the same is made up of a plurality of substantially square open frames 1. It is to be noted that 85 these frames are made from relatively wide strips of metal and when in use the lower edges thereof are directly on the ground, providing good leveling surfaces. To accomplish the desired results and to insure 90 effectiveness of operation, the frames are positioned corner to corner and are arranged in transverse and longitudinal spaced rows and one corner of each frame is directed toward the front so that the relatively wide 95 side portions 2 will effectively deflect the dirt toward the gutters and in cases of the central frames, deflect the dirt in front of adjacent succeeding frames to be evenly spread and carried into small recesses in the 100 road surface to fill the same. The corners of each frame are flattened slightly as indicated at the points 3 and these flattened portions are provided with relatively large openings 4 which serve a purpose to be hereinafter set 105 forth. As previously pointed out, I make use of novel means for connecting the various frames together so that they will be capable of assuming different positions with respect to one another to accommodate the 110 irregular contours. The means employed for accomplishing this end consist in each

instance of a bolt 5 which is extended through the openings 4 in adjacent frames, the threaded end thereof having a nut 6 arranged thereon to connect the frames together. Inasmuch as this bolt is smaller in diameter than the relatively large opening 4 through which it is passed, it is obvious that the desired relative movement of the frames is permitted. I am led to state at this point that it is desirable to so devise the drag so that only the forward frames are allowed to have free relative movement and to so connect the rear frames as to retain them in a substantially horizontal plane so that they will not drag the filling from hollows in the road in which it has been spread by the front frames. I therefore direct attention to the rear portion of the device shown in Fig. 1 wherein it will be seen that relatively long bolts or rods 7 are pressed through several of the frames of the longitudinal rows. These rods serve to hold the frames through which they pass in a substantially horizontal plane yet permit the same to rock on them to accommodate irregularities in the road surface. Referring now to the forward end of the drag, it will be seen that a transversely disposed channel-shaped member 8 is loosely connected with the foremost transverse row of frames and that angle bars 9 are extended along the outermost longitudinal rows of frames and are bolted or otherwise detachably connected at their forward ends to the member 8. The frames of the outermost longitudinal rows are, of course, loosely connected with these angle bars 9 as shown and in order to retain the bars 9 in properly spaced relation and to insure rigidity of construction, I make use of a pair of diagonal braces 10 which are secured at the forward ends to the cross-member 8 by the same fastenings which serve to connect the side bars 9 thereto. Hook-bolts 11 are fastened to the cross-member 8 at spaced points and these constitute means to permit connections of the chains or other hitching devices for the horses to the drag. It is to be noted that the top brace member is arched at its center as indicated at 12 to enable it to extend across the other brace.

Referring now to the slightly modified form of the invention shown in Fig. 3, it will be seen that this form of the drag is practically the same as that hereinbefore described with the exception that the side bars 9, braces 10 and rods 7 are omitted. This form of drag is intended to be used on country roads where it is not absolutely necessary to level the same accurately. The form of the drag first described is preferred and is especially designed for use on speedways, race tracks, and on other paths of travel where extremely smooth surfaces are necessary. The form of the invention disclosed in this Fig. 3 is flexible from end to

end and side to side and does not act exactly like the one first described and as set forth, this form of the invention is desirable for use on rough country roads wherein great flexibility and much movement between the various frames is necessary to enable the device to conform to the irregular surface of the roads.

Referring now to the other modified form of the invention disclosed in Fig. 5, it will be seen that the frames 12 are substantially diamond shaped instead of shaped like those frames already described. This shape of frame will be desirable in many instances to replace the type previously shown and described. Other than the change in shape of the frame, this form of the invention is exactly like that form last described and shown more particularly in Fig. 3. These diamond shaped frames are, like those already described, loosely and pivotally connected together by the means already shown and described in detail. Therefore, the same reference characters will apply. It is, of course, understood that these particularly shaped frames may also be used in the first described form of the invention.

In use, draft of any kind is applied to the device through the medium of the attaching hook 11 and cross-member 8 and the device drawn over the road so that the various frames are successively brought into contact with the lumps of dirt, to break them up and spread the dirt evenly over the entire surface of the road. When employing the form of the invention disclosed in Fig. 3, the parts 8 and 11 can be detached from the foremost transverse row of frames and can be connected to the rear transverse row or side longitudinal rows to enable the device to be moved across the road or in any desired direction. As before set forth, this is advantageous because it permits the frames to be worn evenly.

Practical use of drags constructed in accordance with this invention has disclosed the fact that when continually drawn in one direction, the forward portion of the lower edges of the sides 2 of the frames become rounded, whereas the corresponding parts of the diverging portions of the same frames become worn in such a way as to provide cutting edges. In this respect, the device is self-sharpening. Consequently, when the drag is moved in a reverse direction, the sharpened edges of the frames operate to a more effective extent.

The foregoing description, taken in connection with the drawings will doubtless be found sufficient to enable persons familiar with road drags to obtain a clear understanding of the invention and the various features of the particular device shown and described together with the advantages accomplished thereby. In view of this, a more

lengthy and detailed description is thought unnecessary.

Since probably the best results may be obtained with the construction and arrangement herein shown and described, this is taken as the preferred embodiment of the invention. However, I wish it to be understood that minor changes coming within the scope of the invention as claimed may be resorted to if desired.

I claim:

1. A road drag comprising a plurality of substantially square frames adapted to have the lower edges of their side portions in direct contact with the ground, the corners of said frames being flattened and disposed opposite one another, said flattened corners being provided with relatively large openings, and bolts of less diameter than the openings passing therethrough to connect the several frames together in a manner to permit free relative movements.

2. A road drag comprising a plurality of frames loosely connected together at their corners, and rods connected with a plurality of the rear frames for disposing the frames in the substantial horizontal plane, but permitting said frames to rock from side to side on said rod.

3. A road drag comprising a plurality of substantially square open frames designed to directly engage the ground, said frames being arranged corner to corner and disposed in transverse and longitudinal parallel rows with one corner of each frame disposed toward the front, means for connecting said frames together to permit free rela-

tive movement thereof, a cross member connected with the foremost transverse row of frames, side bars connected with the outermost longitudinal row of frames, braces crossing one another at their centers and connected at their ends with said side bars and cross-bar, and means associated with the rear transverse rows of frames for connecting the latter together and disposing them in the same horizontal plane.

4. A road drag comprising a plurality of substantially square open frames to rest directly upon the ground, said frames being disposed in transverse and longitudinal parallel rows with one corner of each frame disposed towards the front, the corners of each frame being flattened and disposed opposite the corners of the adjacent frame, said flattened corners being provided with relatively large openings, connecting members passing loosely through said openings to connect the frames together and to permit relative movement thereof, longitudinal transversely spaced rods passing through openings in the corners of the rear frames to render the rear portion of the drag substantially rigid while permitting free flexing of the forward portion, a cross bar loosely connected with the foremost transverse row of frames, and side bars connected at their forward ends with said cross bar and also having connection with the outermost longitudinal rows of frames.

In testimony whereof I have hereunto set my hand.

INGEBRIGT J. GLERUM.
